(57) **CLAIM**

The ornamental design for a robotic apparatus for item retrieval and transport, as shown and described.

DESCRIPTION

FIG. 1 is a perspective view of a robotic apparatus for item retrieval and transport according to a first embodiment showing our new design;

FIG. 2 is a front elevational view of the embodiment of FIG. 1;

FIG. 3 is a rear elevational view of the embodiment of FIG. 1;

FIG. 4 is a right side elevational view of the embodiment of FIG. 1;

FIG. 5 is a left side elevational view of the embodiment of FIG. 1;

FIG. 6 is a top plan view of the embodiment of FIG. 1;

FIG. 7 is a perspective view of a robotic apparatus for item retrieval and transport according to a second embodiment showing our new design;

FIG. 8 is a front elevational view of the embodiment of FIG. 7;

FIG. 9 is a rear elevational view of the embodiment of FIG. 7;

FIG. 10 is a right side elevational view of the embodiment of FIG. 7;

FIG. 11 is a left side elevational view of the embodiment of FIG. 7; and,

FIG. 12 is a top plan view of the embodiment of FIG. 7. The broken lines show portions of a robotic apparatus for item retrieval and transport which form no part of the claimed design. The jagged parallel lines enclosed with brackets, as shown in FIG. 1 and FIGS. 4 through 11, represent a break in the claimed design. Anything that appears between the jagged parallel lines enclosed within the brackets forms no part of the claimed design.
